UNITED STATES PATENT OFFICE

172,505

COMBINED LOCKET AND BROOCH

Adolph Katz, Providence, R. I., assignor to Coro, Inc., New York, N. Y., a corporation of New York

Application September 2, 1953, Serial No. 26,685

Term of patent 7 years

(Cl. D45—15)

To all whom it may concern:

Be it known that I, Adolph Katz, a citizen of the United States of America, residing in Providence, county of Providence, and State of Rhode Island, have invented a new, original, and ornamental Design for a Combined Locket and Brooch, of which the following is a specification, reference being had to the accompanying drawing, forming part thereof.

Fig. 1 is a plan view of a combined locket and brooch showing my new design.

Fig. 2 is an edge view thereof.

Fig. 3 is a plan view thereof showing the locket in an open condition, with portions of the brooch omitted for convenience of illustration only;

Fig. 4 is an edge view thereof taken from the bottom of Fig. 3; and

Fig. 5 is a plan view thereof taken from the rear of Fig. 3.

I claim:

The ornamental design for a combined locket and brooch, substantially as shown and described.
